CLAIM

The ornamental design for a combined reversible sprinkler nozzle and support ring, as shown and described.

DESCRIPTION

FIG. 1 is a top perspective view of a combined reversible sprinkler nozzle and support ring showing my new design;

FIG. 2 is a bottom perspective view thereof;

FIG. 3 is a bottom plan view thereof;

FIG. 4 is a top perspective view of a second embodiment thereof;

FIG. 5 is a bottom perspective view of FIG. 4;

FIG. 6 is a bottom plan view of FIG. 4;

FIG. 7 is a top perspective view of a third embodiment thereof;

FIG. 8 is a top perspective view of a fourth embodiment thereof;

FIG. 9 is a top perspective view of a fifth embodiment thereof;

FIG. 10 is a top perspective view of a sixth embodiment, thereof;

FIG. 11 is an enlarged top plan view of the embodiment of FIG. 6; and

FIG. 12 is a cross sectional view taken on line 12—12 of FIG. 11.
